(57) **CLAIM**

The ornamental design for an American-type hammer, as shown and described.

DESCRIPTION

FIG. 1 is a perspective view of the American-type hammer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The handle is depicted in broken line form as it is not considered part of the claimed design.
